GAUGE

Isaac T. Morris, Vancouver, British Columbia,
Canada

Application April 7, 1938, Serial No. 200,797

2 Claims. (Cl. 33—75)

This invention relates to a gauge.

It aims to provide an improved tool adapted to perform the function of various separate tools and for instance that of a gauge, level and plumb, rule, square, protractor, bevel square, try square, miter square, etc.

The more specific objects and advantages will become apparent from a consideration of the description following taken in connection with

10 accompanying drawing illustrating an operative embodiment.

In said drawing:

Figure 1 is a view in side elevation, partly broken away, of the improved gauge;

15 Figure 2 is a plan view of the parts of Figure 1;

Figure 3 is a detail section taken on the line 3—3 of Figure 1;

Figure 4 is a detail section taken on the line 4—4 of Figure 1;

20 Figure 5 is a view showing the invention in connection with a timber, functioning as a plumb, and

Figure 6 is a plan view of the invention in connection with a plank showing use as a bevel.

Referring specifically to the drawing wherein like reference characters designate like or similar parts, a saw is shown as having a blade 10 with a usual toothed cutting edge 11 and with a usual handle 12 detachably secured to the blade 10 as at 13. Said handle has the usual opening 14 to accommodate the fingers.

The straight edge of the saw blade 10 is calibrated as at 15 so that it may be used for measuring or as a rule.

35 A pivot element 16 pivotally secures a miter block 17 to the blade of the saw and it normally abuts the forward edge portion 18 of the handle 12. Adjacent the pivotal end of the miter block 17, a protractor 19 is delineated in any suitable 40 way on the saw blade 10 and the miter block may be freely moved to any desired angle on the protractor.

Said miter block 17 is provided with a spirit bulb or the like as at 20 whereby the miter block 45 also constitutes a level. It will be noted that the blade 10 is provided with an opening therethrough as at 21, so that the leveling means 20 may be observed in some positions. Such leveling means is adjacent the edge 18 so that it will be protected thereby and danger of fracture or 50 injury minimized.

In order to operate the block 17 and secure it at various angles, a link 22 is pivoted thereto at 23 and it has an elongated slot at 24 through 55 which a winged screw 25 passes and which is screw threaded into the handle 12. Tightening of the screw will bind the link 22 against the

handle and thus secure the block 17 in any desired position. Particular attention is called to the fact that the link is adjacent the opening 14 of the handle, so that the hand engaging the latter may also engage the link, in the adjustment of the block, to give a more rapid and accurate adjustment thereof and also so as to better hold it when the adjustment is secured and the next step is to tighten the screw 25.

In Figure 5, the combination saw is shown in 10 use as a plumb, in combination with a structural element 26.

In Figure 6, the combination saw is shown in connection with a plank 27, functioning as a bevel.

It will be obvious, that in lieu of the block 17 and the remaining improvements being shown on one side of the blade only, that they may also be duplicated on the other side of the blade, if preferred.

Various additional uses will become apparent to the artisan.

I claim as my invention:

1. A tool of the class described having a blade and a handle extending therefrom, said blade having a straight edge, a miter block pivoted to the blade inwardly of said edge and normally disposed against the adjacent end of the handle, the outer face of the block being in the same plane as the adjacent face of the handle, said handle having a hand hole therethrough, rearwardly extending link means disposed against said faces and pivoted to the block and operable to adjust the block and having a portion disposed relatively close to the lower extremity of the hand hole for the purpose specified, and clamping means on the handle engageable with the link and constraining it to disposition in the position mentioned.

2. A tool of the class described having a blade and a handle extending therefrom, said blade having a straight edge, a miter block pivoted to the blade inwardly of said edge and normally disposed against the adjacent end of the handle, the outer face of the block being in the same plane as the adjacent face of the handle, said handle having a hand hole therethrough, rearwardly extending link means disposed against said faces and pivoted to the block and operable to adjust the block and having a portion disposed relatively close to the lower extremity of the hand hole for the purpose specified, clamping means on the handle engageable with the link and constraining it to disposition in the position mentioned, and protractor means delineated on the blade adjacent the pivotal axis of the block.

ISAAC T. MORRIS.
